CLAIM

The ornamental design for a connecting pipe for vacuum cleaner, as shown and described.

DESCRIPTION

1. Connecting pipe for a vacuum cleaner

1.1 : Perspective

1.2 : Front

1.3 : Back

1.4 : Left

1.5 : Top

1.6 : Bottom

The broken lines depict portions that form no part of the claimed design; the dash-dot broken lines define the boundary of the claimed design and form no part thereof; reproduction 1.1 is a front perspective view of the connecting pipe for vacuum cleaner; reproduction 1.2 is a front view thereof; reproduction 1.3 is a back view thereof; reproduction 1.4 is a left view thereof where the right view is a mirror image; reproduction 1.5 is a top view thereof; reproduction 1.6 is a bottom view thereof; this is a design for a connecting pipe for vacuum cleaner which connects the main body of the

(Continued)

vacuum cleaner and the nozzle part, and has a lever to allow the three fingers to be positioned naturally.
